UNITED STATES PATENT OFFICE.

MATHAUS HOLM, OF SAN FRANCISCO, CALIFORNIA.

WIRE-CUTTING ATTACHMENT FOR SMALL-ARMS.

1,181,223.

Specification of Letters Patent.

Patented May 2, 1916.

Application filed January 8, 1916. Serial No. 70,031.

To all whom it may concern:

Be it known that I, MATHAUS HOLM, a citizen of the United States, residing in the city and county of San Francisco and State of California, have invented certain new and useful Improvements in Wire-Cutting Attachments for Small-Arms, of which the following is a specification.

The present invention has for its object 10 the provision of an appliance which may readily be attached to a rifle or other small arm, to enable the holder thereof to easily and quickly cut wires or similar objects, without interfering in any way with the 15 normal use of the arm.

The device is designed primarily for use 20 by soldiers, to enable them to rapidly break down wire barriers and entanglements, and to do away with the necessity of providing each man with a separate wire cutting 25 appliance. By the use of the device embodying the present invention, the soldier is enabled to cut such wire barriers without removing either hand from his gun, which is a feature of considerable advantage, particularly when a charge is being made. Moreover, the device is mounted upon the muzzle end of the arm, so that the user, having the length of said arm between himself 30 and the wire, is not at all apt to become entangled therein or injured in case said wire is barbed, and by grasping the wooden parts of the stock, he will escape injury even if the wire be charged with electricity. 35 These and other advantages will be made apparent by the following specification.

In order to comprehend the invention, reference should be had to the accompanying sheets of drawings, wherein—

40 Figure 1 is a perspective view of the wire cutting attachment applied to a rifle with a bayonet affixed thereto, showing a wire in position to be cut. Fig. 2 is a detailed view similar to Fig. 1, showing the wire cut and 45 the position of the projectile immediately after it has actuated the cutting device. Fig. 3 is an enlarged detailed elevation, showing the preferred manner of mounting the device upon the bayonet. Fig. 4 is a 50 plan view of the device. Fig. 5 is a section on the line $x-x$ of Fig. 3, taken in the direction of the arrows. Fig. 6 is a section on the line $y-y$ of Fig. 3, taken in the direction of the arrows.

55 In the drawings, and referring particularly to Figs. 1, 2 and 3 thereof, the numeral

1 designates a small arm, which for the present purposes of illustration is represented as a standard army rifle, having a barrel 2 and a wooden guard 3, although it is to be understood that small arms of other types may be used. The rifle has mounted in the usual manner upon its muzzle end a bayonet 4, the same being provided with the customary handle 4' and guard 5 adapted to fit over the end of the barrel 2.

A rectangular shell 7 is adapted to fit over the bayonet blade 4, and is provided with a set screw 8 adapted to seat in a socket 9 in the side of said bayonet blade 4, to secure said shell 7 upon said bayonet blade 4. The shell 7 carries two spaced upwardly projecting lugs 10, between which lies the rear end of a finger 11, pivoted upon a pin 12, and disposed longitudinally above the bayonet blade 4.

The blade 4 is formed with a cutting edge or blade 13 upon its upper side. An opposite coacting blade 14 is carried by the under side of the finger 11, the two forming 80 shears adapted to cut a wire 15, as shown in Figs. 1 and 2 of the drawings, and described more fully hereinafter. A spring 16, Fig. 3 of the drawings, normally retains said finger 11 in its lowermost position, so that its outer or forward end 11', which is upset, is held out of the path of the projectile 17, Fig. 2 of the drawings, issuing from the barrel 2, and therefore does not in any way interfere with the normal use of the arm. The lower part of the shell 7 is forwardly extended, as shown at 18, to provide support for the bayonet blade 4 under the cutting edge 13 thereof.

When it is desired to use the wire cutting 95 attachment, the back or upper edge of the bayonet blade 4 is placed against the wire 15, and the arm thrust forward to bring said wire between the opposite cutting blades 13 and 14, as shown in Fig. 1 of the 100 drawings. The presence of the wire between said blades raises the finger 11, so that its outer end 11' lies in the path of the projectile 17. The arm is then discharged, and the projectile 17, striking said finger 11, 105 forces the same downward toward the bayonet 4, and the wire 15 is cut by the opposite blades 13 and 14, as shown in Fig. 2 of the drawings. The projectile 17 is, of course, deflected by its contact with the finger 11, 110 and therefore has no other purpose than to actuate the wire cutting mechanism.

The invention has hereinbefore been described in its preferred form, but I do not wish to be construed as limiting myself thereto, for the reason that many changes 5 may be made in the form and construction of the device, without departing from the spirit of the invention, and I therefore wish to claim the invention as broadly as I may.

Having thus described my invention, what 10 I claim as new and desire to protect by Letters Patent is:—

1. A wire cutting attachment for small arms comprising cutting devices for engaging a wire, and means lying in the path of 15 the discharged projectile of the arm and actuated thereby to operate said cutting devices to cut said wire.

2. The combination with a small arm having a bayonet affixed to the muzzle end 20 thereof, of wire cutting means carried by said bayonet and adapted to be actuated by the discharged projectile of said arm.

3. The combination with a small arm having a bayonet affixed to the muzzle end 25 thereof, of wire cutting means removably mounted upon said bayonet and adapted to be actuated by the discharged projectile of said arm.

4. The combination with a small arm 30 having a bayonet affixed to the muzzle end thereof, of cutting devices mounted upon said bayonet and adapted to engage a wire, and means associated therewith and adapted to be actuated by the discharged projectile 35 of the arm to operate said cutting devices to cut said wire.

5. The combination with a small arm having a bayonet affixed to the muzzle end thereof, of cutting devices mounted upon 40 said bayonet and adapted to engage a wire, and means lying in the path of the discharged projectile of the arm and actuated

thereby to operate said cutting devices to cut said wire.

6. The combination with a small arm 45 having a bayonet affixed to the muzzle end thereof, of cutting devices mounted upon said bayonet and adapted to engage a wire, means adapted to be inserted into the path of the projectile of the arm to be actuated 50 thereby to operate said cutting devices to cut said wire, and means for holding said operating means out of the path of the projectile except when a wire is engaged by said cutting devices.

7. The combination with a small arm having a bayonet affixed to the muzzle end thereof, of a fixed cutting member carried by said bayonet, a tubular shell adapted to surround said bayonet, and a movable cutting 60 member carried by said shell and adapted to be actuated by the discharged projectile of the arm to coact with said fixed cutting member to cause the same to cut a wire interposed therebetween.

8. The combination with a small arm having a bayonet affixed to the muzzle end thereof, of a fixed cutting member carried by said bayonet, a tubular shell adapted to surround said bayonet, and a movable cutting member carried by said shell, and means 70 associated therewith and adapted to be inserted into the path of the projectile of the arm to be actuated thereby to operate said movable cutting member to cause the same to coact with said fixed cutting member to cut a wire interposed therebetween.

In testimony whereof I have signed my name to this specification in the presence of two subscribing witnesses.

MATHAUS HOLM.
